PIVOTED VANE DAMPER

Hoyt K. Veber, Kellogg, Iowa, assignor to Titus Manufacturing Corporation, Waterloo, Iowa, a corporation of Iowa

Filed June 6, 1960, Ser. No. 34,094
5 Claims. (Cl. 251—212)

This invention relates to flow control devices adapted to control the flow of a fluid to a passageway. In one application, the flow control devices can be used in air ducts to control the amount of air permitted to pass through said ducts.

The invention also relates to the combination of an air diffuser with the flow control device mounted in the neck portion thereof and to flow control devices especially adapted for mounting in the neck of an air diffuser. The invention also relates to improvements in the mounting of pivotal vanes or plates and in mechanism for actuating the pivotal action of said vanes or plates.

Briefly, the flow control devices or dampers of the present invention comprise a series of adjacent, pivotable vanes or plates adapted to lie in a flat plane and substantially block off air flow through a passage when they are in this position. When used in combination with an air diffuser, the flow control devices or dampers may have a supporting frame including a plurality of spider arms with means at the ends of the spider arms for mounting the damper on mounting brackets provided on the inner wall of the neck of the diffuser. In this position, the damper is readily accessible for adjustment to provide desired quantity of air flow through the diffuser and thence into a room. The actuating mechanism for the vanes is a hollow member movable in a direction normal to the plane of the vanes when the damper is in closed position. This hollow member has means which cooperates with a part of the vanes to cause the vanes to pivot when the hollow member is moved.

My invention also relates to a novel means for pivotally mounting a vane or plate on a frame, which means facilitates the ready assembly of the pivotal vanes on the damper. In this aspect of my invention, the vane has on one end a pin or axle which is pivotally-mounted in a closed bearing, which may be a simple hole in a plate. The other end of the vane has a pin or axle pivotally-mounted in an open saddle bearing. The vane is held in the two bearings by a bias means, preferably a spring, which urges the vane downwardly in the open saddle bearing and is positioned adjacent the saddle bearing. This spring also serves as the means for urging the vane to its home position.

An embodiment of my invention is shown in the drawings wherein:

FIG. 1 is a partial, top plan view of a diffuser with an embodiment of a damper of my invention mounted in the neck of the diffuser. The damper is shown in the fully open position with the vanes lying parallel to the axis of the neck of the diffuser;

FIG. 2 is a partial, bottom plan view of the diffuser and damper of FIG. 1 with the damper vanes in fully closed position, wherein the vanes lie in a plane transverse to the axis of the neck of the diffuser. The inner deflector members have been removed to facilitate illustration of the damper;

FIG. 3 is a side elevation of the damper shown in FIGS. 1 and 2 with the damper vanes in the closed position;

FIG. 4 is a similar side elevation with the damper vanes partly open;

FIG. 5 is a cross-sectional view taken on section 5—5 of FIG. 2; and,

2

FIG. 6 is a top plan view of a segment of one of the damper vanes illustrated in FIGS. 1—5.

The diffuser with which the damper is used may be of any design having an outwardly-flaring, outer, hollow shell with means positioned within the shell or below the same for deflecting air outwardly. For purpose of illustration, a round diffuser has been shown in the drawing although other forms may be used, such as square or oblong or the like. The diffuser shown in the drawing comprises an outwardly-flaring, outer, hollow member 10 having a cylindrical neck portion 12. The outer edge of the member 10 has a peripheral ceiling gasket 14 of compressible material. The hollow member 10 has an outwardly-flaring segment 16 which is arcuately bent at 18 to form a rearwardly-extending circular periphery 20 with a terminal edge 22.

The damper is mounted in the neck 12 and is composed of three vane pairs, e.g., pairs of butterfly vanes 24, 26 and 28 which are pivotable toward each other about adjacent parallel pivot axes for each pair. When the vane pairs 24, 26 and 28 are in the fully closed position, wherein they lie in a common plane, they substantially cover the cross-sectional area of the neck 12 and thereby substantially preclude flow of air from a supply duct 25 through the diffuser.

The framework of the damper is made up of spider arms 30, 32 and 34, whose outer ends have downwardly directed segments 36. Each of the segments 36 has a terminal tab 38, which is formed by stamping out portions 30 from the segments 36. These tabs can be twisted to lock the damper in the neck of the diffuser when the segments 36 are mounted in the mounting brackets in the neck of the diffuser.

The mounting brackets 40 for each of the spider arms 35 are spaced slightly from the inner surface of the neck of the diffuser to permit the segments 36 to be inserted between the brackets 40 and the neck 12 of the diffuser. The space between the brackets 40 is open on three sides to permit the mounting of the damper by rotating the segments 38 into the open sides of the space between the mounting brackets 40 and the neck 12. When the damper is positioned in the neck, the tabs 38 may then be twisted to lock the damper in the mounting brackets.

The mounting brackets 40 are offset portions of mounting plates 42 spot-welded to the neck 12. The mounting plate 42 also has an offset segment 44 which has an inclined upper surface with a detent or shoulder 45. The offset portion 44 constitutes a means for mounting the radial spider arms 46 of inner deflector members of the diffuser in the outer hollow member 10. The means by which this is done are described more fully in application Ser. No. 682,164, filed by Robert W. Titus and Francis J. Coates on September 5, 1957, now Patent No. 2,958,272.

55 The spider arms 46 support one or more deflector members of similar, though smaller configuration than the outer member 10 concentrically within the hollow member 10. In the view shown in FIG. 1, these spider arms 46 support outwardly-flaring frusto-conical deflector members 50 and 52. The means by which these members are supported on the spider arms is also described in said application of Robert W. Titus and Francis J. Coates.

65 The spider arms 30, 32 and 34 are spot-welded on a ring 54. A cup-shaped, hollow member 56 with a peripheral flange 58 is spot-welded on the other side of the ring 54. The hollow member 56 has an internally threaded nut 60 spot-welded on the inner wall of the cup-shaped member 56.

70 A screw 62 is threaded in the nut 60 and extends through an opening 64 in the bottom wall of the cup 56. The end of the screw is a pin 66 extending through an

opening in a hollow, cup-shaped member 70. The end of the pin 66 is deformed to form a rivet head 68. The pin 66 and rivet head 68 are sufficiently loose so that the pin 66 of the screw 62 rotates in the opening of the cup-shaped member 70.

The cup-shaped member 70 is mounted over the cup-shaped member 56 and is slidably axially therealong by rotation of the screw 62. This cup-shaped member has three flange segments 72 which are divided by slots 74 in the flange. The slots 74 are of a width slightly greater than the width of upwardly-directed segments 77 of the radial supporting arms 76, which arms support the pivotable vanes or plates 24, 26 and 28 in the manner herein-after described.

The outer ends of the arms 76 have upwardly-extending segments 78. The segments 77 and 78 contain bearings for pivotably mounting the vanes on the damper frame. The segments 77 each having a pair of holes 80. Each hole serves as a closed bearing for pins or axles 82 of the vanes. The opposite end of the axis of rotation of the vanes is made up by pins or axles 84 rotatably supported in saddle bearings 86 in the upper ends of segments 78. The vanes are held in the saddle bearings by a coil spring 88 seated in grooves 90 in the radial arms 76. The springs 90 are attached at their ends to the vanes at a point adjacent the saddle bearings by hooking the ends 94 of the springs 88 through small apertures 92 in the vanes. The use of open saddle bearings in the segments 78 facilitates the assembly of the vanes on the framework of the damper by providing a means for readily inserting the pins or axles in an open bearing. It is much easier to assemble the vanes in this combination than in the case of a closed bearing at each end of the vane.

The lineal movement of the hollow, cup-shaped member 70 is translated into pivotal movement of the vane pairs 24, 26 and 28 through followers or riders 96 on each of the vanes. These followers or riders are integral parts of the vanes and extend downwardly therefrom. Their bottom edge is an arcuate surface which rides on the flange segments 72 of the cup-shaped member 70. As the cup-shaped member 70 is moved axially by the screw 62, the linear moving segment 72 of the cup-shaped member 70 acts on the followers or riders 96. This creates a lever arm through the followers 96 on each of the vanes to cause them to pivot about their edges and, thus, open the damper. The springs 88 hold the damper vanes in the adjusted position and their tension causes the damper to return toward the closed position when the cup-shaped member 70 is returned toward the home position shown in FIGS. 3 and 5.

The damper vanes and their pins or axles 82, 84, as well as the rider or follower 96, may be made of a single stamping from a flat, heavy gauge metal sheet. The stamping is made to form the small pins or axles 82, 84 integral with the damper vanes and similarly forming the downwardly-extending riders or followers 96 from the metal sheet. A segmental view of such a damper vane is shown in FIG. 6.

The novel features of my invention reside in the pivotable vane and actuator mechanism associated therewith, the means for mounting of the damper in a diffuser, the means for mounting the pivotable vanes on a frame, the structure of the vanes, and other features of the invention which appear in the foregoing specification and the following claims.

The invention is hereby claimed as follows:

1. In a flow control device, a frame, a plurality of vanes pivotably mounted on said frame, said vanes adapted to be pivoted to lie in a common plane, a bearing fixedly mounted on said frame, a hollow actuator member mounted about said bearing member and slidable thereon in a direction substantially normal to said plane, a threaded shaft threaded in said bearing member, said shaft bearing against said hollow actuator member, said hollow actuator member having a bearing surface, and

4
a follower on each of said vanes riding on said bearing surface to cause said vanes to pivot when the actuator member is moved in a direction substantially normal to said plane by rotation of said threaded shaft.

5 2. In a flow control device, a frame comprising a plurality of radially extending arms, vanes pivotally mounted on said arms, said vanes adapted to be pivoted to lie in a common plane, a bearing member on said frame at the hub of said radial arms, a hollow actuator member slidably about said bearing member in a direction substantially normal to said plane, a bearing flange on said hollow actuator member, and a follower on each of said vanes having an arcuate edge riding on said bearing flange to cause said vanes to pivot when the hollow actuator member is moved in a direction substantially normal to said plane.

10 3. In a flow control device, a frame including an arm, a pair of juxtaposed, closed, pivot bearings at one end of said arm, a pair of juxtaposed, open saddle bearings at the other end of said arm, a pair of vanes, each vane pivotally supported in one of each of said bearings by projecting pins aligned at opposite ends of one side of each of said vanes, said pins forming pivot axes which are adjacent and substantially parallel, means to cause said vanes to pivot about their respective axes, each of said vanes being made from a single stamping having a straight side with a pin projecting at each end of said side to form the pivot axes of said vanes, each of said vanes further having a tab substantially normal to the frame of said vane, said tabs having an arcuate edge which rides on a bearing surface of said means for pivoting said vanes, and bias means acting on each of said vanes adjacent said saddle bearings for holding said pins in said saddle bearings and urging said vanes to a home position.

15 4. In a flow control device, a frame, pair of butterfly vanes with adjacent pivot axes pivotally mounted on said frame, said vanes adapted to be swung upwardly about their pivot axes from a position in which they lie in a common plane, an actuator movably mounted on said frame in a direction normal to said common plane, a bearing surface on said actuator below said vanes when they are in said common plane, a follower member depending downwardly from the underside of each vane, and an arcuate outer edge on each follower member riding on said bearing surface to cause said vanes to pivot when said bearing surface is moved upwardly toward said common plane.

20 5. In a flow control device, a frame including an arm, a pair of juxtaposed, closed, pivot bearings on one side of and at one end of said arm, a pair of juxtaposed, open saddle bearings on said one side of and at the opposite end of said arm, a pair of vanes, each vane being pivotally supported in one of each of said closed and saddle bearings by projecting pins on said vanes, said pins aligned at opposite ends of one side of each of said vanes, said pins forming pivot axes which are adjacent and substantially parallel, means to cause said vanes to pivot about their respective axes, and a spring connected to said vanes and extending therebetween adjacent said saddle bearings and across the side of said arm opposite said one side of said arm to hold said pins in said saddle bearings and urging said vanes to a home position.
